UNITED STATES PATENT OFFICE.

JAMES A. DAWLEY, OF DENVER, COLORADO.

DESIGN FOR A FINGER-RING.

SPECIFICATION forming part of Design No. 21,691, dated July 5, 1892.

Application filed September 19, 1891. Serial No. 406,263. Term of patent 3½ years.

To all whom it may concern:

Be it known that I, JAMES A. DAWLEY, a citizen of the United States, residing in Denver, in the county of Arapahoe and State of Colorado, have invented and produced a new and original Design for Finger-Rings, of which the following is a specification, reference being had to the accompanying drawings, forming a part thereof.

Figure 1 is a view of a finger-ring in cross-section. Fig. 2 is a front view of a finger-ring, showing my design.

The leading feature of my design consists

in the several elements which comprise the figures of a dove 2, bearing in its mouth a palm-branch, a log of wood 3, with an ax 4, and a wedge 5, driven into it, and a beetle 6, lying beside the same.

What I claim is—

The design for finger-rings, herein shown and described.

JAMES A. DAWLEY.
